UNITED STATES PATENT OFFICE.

SEVERN D. SPRONG, OF BROOKLYN, NEW YORK, ASSIGNOR OF ONE-HALF TO
METROPOLITAN ENGINEERING COMPANY.

LOAD-EQUALIZER FOR GENERATORS.

No. 856,741.

Specification of Letters Patent.

Patented June 11, 1907

Application filed March 26, 1906. Serial No. 308,020.

To all whom it may concern:

Be it known that I, SEVERN D. SPRONG, a citizen of the United States, residing at Brooklyn, in the county of Kings and State of New York, have invented a certain new and useful Improvement in Load-Equalizers for Generators, of which the following is a specification.

The object of the invention is to maintain automatically a uniform distribution of load between generating units operating in parallel, or any predetermined distribution of load among said units.

The principle of the invention is to utilize the difference due to abnormal load on any one unit, as compared with the average load on all the others, in order to actuate means for bringing the abnormal load back to normal. One embodiment of this principle is hereinafter set forth in an apparatus wherein are combined a plurality of generating units and means controlled by the establishment of a differential between the average load on each of said units, and the actual load on one of them, for causing said last named unit to assume its distributive share or some predetermined share of the whole load.

In the accompanying drawings—Figure 1 is an elevation of my apparatus. Fig. 2 is a vertical section on the line x: x. of Fig. 1. Fig. 3 is a plan view and Fig. 4 is an enlarged detail view showing the device for mechanically connecting two or more of the levers 6. Fig. 5 illustrates diagrammatically one device through which, in my present apparatus, a dynamo may be regulated by its associated motor.

Similar numbers and letters of reference indicate like parts.

Upon the base 1 are two solenoids A, B, connected in series with the three phase generating unit C. The core 2 of solenoid A is supported upon one arm of a lever 3 pivoted in standard 4. The core 5 of solenoid B is supported upon one arm of a lever 6, pivoted in standard 7. The opposite arm of lever 6 has a yoke 8, in the arms of which are contact screws 9 and 10. The opposite arm 11 of lever 3 extends between said screws 9 and 10.

The parts so far described are associated as stated with generating unit C, which is one of the units operating in parallel. A similar apparatus is associated with every other unit. Thus, as shown in Fig. 3, the solenoids D, E,

control pivoted levers and contacts, the same as already described, and are connected in series with generating unit F. The dotted circles G and H indicate solenoids connected with still another unit, not shown. The solenoids of each pair as A, B, or D, E, or G, H are disposed opposite one another, line e. f. Fig. 4. The solenoids A, D, G of the different pairs are in line a. b. and the solenoids B, E, H, in parallel line a. d. Fig. 4.

Extending upward from each standard 7 are supports 12, and in the several supports 12 is journaled a rock shaft 13, from which extend fixed arms 14. At the end of each arm 14 is pivoted a downwardly depending rod 15 which is received in a block 16, pivoted, as shown in Fig. 4, in a slot in the lever 6. The rod may be clamped in block 16 by means of the screw 17.

The lever arms 11 form circuit terminals and are all connected to one conductor (+) 75 of the main or bus bar 18. The contact screws 9 and 10 are also circuit terminals and are respectively connected through the reversely wound field coils 19, 20, and armature of a motor 21, to the other conductor (-) of said main or bus bar.

The solenoids A, B, D, E, etc., are all exactly similar. Hence, if any pair as A, B, be considered separately, (the screw 17 being released) it is obvious, that while the contact screws 9 and 10 on lever 6 and the end 11 of lever 3 will move as the load varies, their relative position will remain the same; and so long as the load on A and B remains unchanged, said parts will not make electrical contact. If, however, all of the clamping screws 17 are tightened, thus preventing any sliding of the rods 15 in blocks 16, then the position of the levers 6, and hence of the contact screws carried thereby, will be controlled, not by the load of any one unit C, F, etc., but by the average load on all of the units, and the position of said levers 6, and hence of said screws, will depend upon said average load.

If the load on each unit equals its share of the whole load, then the circuit terminal or end 11 of each lever 3 will maintain its relative position with respect to its associated contact screws 9 and 10 and make contact with neither. But if the load on any one unit becomes either greater or less than its share of the whole load, then the end 11 of lever 3 associated with that unit will

move with respect to contact screws 9 and 10, to close circuit with one screw or the other, with the result that the motor associated therewith receives current from main 5 18 to cause it to rotate in one direction or the other. The motor may then control in any suitable way that unit until it again takes care of its proper share, or some predetermined share, of the load.

10 It will be observed that the armatures of magnets A. D. G. are not mechanically connected and that each of said magnets is free to move its armature and hence the lever 11 controlled thereby in accordance with the 15 load on itself. If this load coincides with the average load which has set lever 6 in position, then the end of lever 11 will not make contact with either terminal 9 or 10 carried by 6. But suppose the load on any dynamo 20 is in excess of the average: Then the magnet A D or G, controlled by that particular dynamo will displace its lever 11 to make contact with one of the two terminals carried by its opposite lever 6 and circuit will be established through the motor to effect proper 25 regulation. The point to be noted is that while the magnets B. F. H are mechanically connected, the magnets A D G are not. Hence a differential is produced between the 30 result of all the magnets B F H acting separately. And this differential regulates the dynamo controlling the particular magnet A D or G. One way of effecting this motor control is illustrated in Fig. 5.

35 a represents an engine, which actuates the dynamo C. The engine valves at b, may be controlled by the link c, connected to the pivoted arm d, which is connected in the usual way to the sleeve e of a ball governor f. And 40 the governor in any suitable manner (not shown) is driven by the engine. Connected by link g to the free end of arm d is a shaft h having a rounded head p, pivoted at i to any fixed support j upon which support the field 45 coils 19 of the motor are fixed.

50 21 is the motor armature fast upon a threaded sleeve k, the end of which may bear against a collar l fixed on shaft h. On sleeve k is a nut m having a sleeve n which as the nut moves travels on a fixed guide bar o. In this way rotation of the nut on the sleeve k is prevented. As the motor armature rotates in one direction or the other, the sleeve k rotates with it and hence the nut m is caused to 55 move in one direction or the other along said sleeve k, thus varying, through the linkage, the amount of weight acting upon the governor sleeve e, and hence the effect of the governor upon the engine valves to vary the 60 engine speed, and thus the speed of rotation of the armature of dynamo C.

Connected to the lever 3 are two inclined guide arms, 22, carrying a weight 23, which may be adjusted by the screw 24. Connected 65 to levers 6 are similar guide arms 25, inclined

in the opposite direction and carrying a weight 26, which may be adjusted by the screw 27. By adjusting the weights 23 and 26 the cores 2 and 5 may be balanced, or by the same means I may change at will the 70 share of the load which any unit may assume. By shifting the weights so as to exert greater or less average, a greater or less load will be maintained on the associated unit, and in this way said unit may be over- or under-loaded 75 at will.

The rods 15 are clamped by screws 17 at points equidistant from their pivot connections to arms 14. If a unit is out of service, its associated apparatus is mechanically disconnected from that belonging to the other units by releasing the screw 17, thus leaving the rod 15 to play freely up and down in its block 16.

I claim:

1. A plurality of generating units and means controlled by the establishment of a differential between the average load on each of said units and the actual load on any one of them, for causing said last named unit to assume its distributive share of the whole load.

2. A plurality of generating units and means controlled by the establishment of a differential between the average load on each of said units and the actual load on any one of them, for causing said last named unit to assume a predetermined share of the whole load.

3. A plurality of generating units and means controlled by the establishment of a differential between the average load on each of a number of said units less than the whole and the actual load on any one of them, for causing said last named unit to assume its distributive share of the load on said number of units.

4. A plurality of generating units and means controlled by the establishment of a differential between the average load on each of a number of said units less than the whole and the actual load on any one of them, for causing said last named unit to assume a predetermined share of the load on said number of units.

5. A plurality of generating units, movable circuit terminals associated with each unit, a plurality of electrically operated devices respectively controlling said units and respectively in circuit with said terminals, and means controlled by the establishment of a differential between the average load on each of said units and the actual load on any one of them, for moving into contact the terminals associated with said unit and thereby closing circuit to the electrically operated device in circuit with said last named terminals.

6. A plurality of generating units, relatively movable circuit terminals associated with each unit, means for initially adjusting

the initial position of the + and - members of each pair of circuit terminals, a plurality of electrically operated devices respectively controlling said units and respectively in circuit with said terminals, and means controlled by the establishment of a differential between the average load on each of said units and the actual load on one of them for moving into contact the terminals associated with said unit and thereby closing circuit to the electrically operated device in circuit with said last named terminals.

7. A plurality of generating units, movable circuit terminals associated with each unit, a plurality of motors respectively controlling said units and respectively in circuit with said terminals and means controlled by the establishment of a differential between the average load on each of said units and the actual load on any one of them, for moving into contact the terminals associated with said unit and thereby closing circuit to the motor in circuit with said last named terminals.

25 8. A plurality of generating units, a plurality of movable mechanically connected circuit terminals actuated by said units, a plurality of independent movable circuit terminals each actuated by one of said units and each in proximity to one of said first named terminals and means in circuit with each pair of approximated terminals for controlling the unit associated with said pair of terminals.

9. A plurality of generating units, a plurality of movable circuit terminals simultaneously actuated by all of said units to take a definite position, a plurality of separate movable circuit terminals each associated with one of said units and actuated thereby, and each disposed in proximity to one of said first named terminals and a plurality of electrically operated devices each in circuit with one of said first named terminals and one of said separate terminals, and each constructed to control the unit associated with said separate terminal.

45 10. In combination with each unit of a plurality of generating units, two solenoids in series circuit with said unit, a movable circuit terminal actuated by one of said solenoids, a movable circuit terminal actuated by the other solenoid and disposed in proximity to said first terminal, a motor in circuit with said terminals and controlling said unit and means for mechanically connecting the several circuit terminals actuated by one set of corresponding solenoids of different pairs.

11. In combination with each unit of a plurality of generating units, two solenoids in series circuit with said unit, a movable circuit terminal actuated by one of said solenoids, a movable circuit terminal actuated by the other solenoid and disposed in proximity to

said first terminal, a motor in circuit with said terminals and controlling said unit and means for mechanically connecting any number less than all, of the circuit terminals actuated by one set of corresponding solenoids of different parts.

12. In combination with each unit of a plurality of generating units, two solenoids in series circuit with said unit, a movable double contact terminal actuated by one of said solenoids, a movable single contact terminal actuated by the other solenoid and disposed in proximity to both contacts of said first named terminal, a motor controlling said unit and in circuit with said terminals and constructed to rotate in one direction or the other in accordance as circuit is established between one or the other contact of said double contact terminal and said single contact terminal, and means for mechanically connecting the several double contact terminals of different pairs of solenoids.

13. Two generating units C, F, a pair of solenoids A, B, in series circuit with unit C, a pair of solenoids E, D, in series circuit with unit F, two pivoted levers 6 vibrated by solenoids B, E, means for mechanically connecting two or more of said levers 6, contact terminals 9, 10 carried by each of said levers 6, two pivoted levers 3 vibrated by solenoids A, D, a circuit terminal 11 carried by each of said levers 3, the terminals 11 being disposed between the terminals 9, 10, a motor in circuit with the circuit terminals 9, 10, 11, associated with solenoids A, B, and controlling unit C, and a motor in circuit with circuit terminals 9, 10, 11, associated with solenoids D, E, and controlling unit F.

14. Two generating units C, F, a pair of solenoids A, B, in series circuit with unit C, a pair of solenoids E, D, in circuit with unit F, two pivoted levers 6, vibrated by solenoids B, E, adjustable weights carried by said levers, means for mechanically connecting two or more of said levers, contact terminals 9, 10, carried by each of said levers 6, two pivoted levers 3 vibrated by solenoids A, D, adjustable weights carried by said levers, a circuit terminal 11 carried by each of said levers 3, the terminals 11 being disposed between the terminals 9, 10, a motor in circuit with the circuit terminals 9, 10, 11, associated with solenoids A, B, and controlling unit C, and a motor in circuit with circuit terminals 9, 10, 11, associated with solenoids D, E, and controlling unit F.

In testimony whereof I have affixed my signature in presence of two witnesses.

SEVERN D. SPRONG.
